UNITED STATES PATENT OFFICE.

SVEN GUSTAF WIGELIUS, OF ESKilstuna, SWEDEN

INTERNAL-COMBUSTION ENGINE.

997,643.

Specification of Letters Patent. Patented July 11, 1911.

Application filed February 9, 1906. Serial No. 300,336.

To all whom it may concern:

Be it known that I, SVEN GUSTAF WIGELIUS, a subject of the King of Sweden, residing at Eskilstuna, Sweden, have invented certain new and useful Improvements in Internal-Combustion Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to gas-motors of the kind wherein a ready-formed gas and air mixture, formed and mixed outside the working cylinder, is introduced into the cylinder, where it burns as it is introduced 20 depending upon the very high temperature arising at the compressing of the air in the cylinder at the compression stroke. The motor in a well known manner coöperates with one or more air compressors (in the 25 drawing two are shown) which compress the air required for operating the machine.

The distinguishing characteristic of the present motor consists therein, that it is arranged like a compound engine with two 30 cylinders, of which the smaller is the combustion cylinder and the larger the expansion cylinder, while the latter after receiving the combustion gases that escape from the combustion cylinder, further utilizes their expansibility. The combustion gases are introduced into the expansion cylinder partly by reason of the rarefaction taking place therein, and partly by means 35 of the compressed-air let into the combustion 40 chamber, which air after forcing the combustion gases into the expansion cylinder, completely cleans the former cylinder and fills it with air. By this mode of operation of the machine both an uninterrupted and 45 constantly effective combustion of the drying-gas mixture entering the working cylinder as well as a sure ignition are attained, the ignition being effected in the known pneumatic way, *i. e.* by compression or spontaneous.

In the annexed drawings, Figure 1 illustrates schematically an entire motor, Figs. 2, 3 and 4, different positions of the piston in the combustion cylinder.

55 The two-cylinder motor, shown as an illustration, has in conformity with the two

cylinders 15 and 16, also two air-compressors, 17 and 18, in which the piston in the larger compressor 17 is directly connected to the piston 53 in the smaller or combustion cylinder, 15, while the piston of the smaller compressor 18 is connected with the piston 54 of the larger, expansion cylinder, 16. The compressors may also, for instance, be driven by means of shaft 39 to which the 60 two pistons, 53 and 54, are connected 90° apart. Both compressors are in such connection with each other that the air compressed in 17 passes into and is subjected to a further compression in 18, so that there 65 results a compression by stages.

The communication between the cylinders 15 and 16 is primarily effected through ports 19 surrounding the combustion cylinder 15 in the center, said ports being formed in the 75 known manner of orifices in the cylinder wall, said orifices opening into an annular chamber 20 or the like, surrounding the cylinder. From this chamber 20 conduit 21 passes to the expansion-cylinder. This latter is provided with an inlet valve and an outlet valve on either side of the piston, in the same manner as the cylinder 15, in Fig. 1. Thus, 22 and 23 are the inlet valves, and 24, 25 are the outlet valves, all being in a 80 suitable manner controlled by a cam-member 37, fastened to a shaft 38. This latter is, by means of a suitable gearing, connected to and driven from the motor-shaft 39, to which end I have shown miter-gears 60 and 61, the latter on shaft 62 which is driven by the miter gears 63 and 64. The combustion cylinder has also on each side of the piston 53 two valves, 26, 27, and 28, 29. All of them are, like the valves for the expansion 95 cylinder 16, controlled by a cam-member 30, likewise fixed on shaft 38. Valves 26 and 28 are inlet valves for compressed air and fuel, and are, by means of conduits 31 and 32, in communication with the compressor 18 or 100 with the pressure-air receiver 33, and by conduits 34 and 35 connected with receptacle 36 containing liquid fuel under pressure. Valves 27 and 29 are cleaning valves and are by means of conduit 52 connected with the 105 compressor 17, from which the compressed air may thus enter and clean the combustion cylinder 15.

The two-cylinder motor works in the following manner: Suppose that the piston 53 in the combustion cylinder has the position shown in Fig. 1, the air and fuel valve 28

is in turn opened. The ignitable driving-gas mixture thus entering the cylinder 15, burns as it enters, depending upon the temperature of the air compressed in the cylinder during the compression stroke, being on account of the high compression higher than the igniting temperature of the fuel, and the piston 53 is moved to the left. The driving-gas mixture is let in and burns in this manner during a greater or less part of the stroke of the piston from the end-position to the ports 19, for instance during one-half of the way, whereupon valve 28 is closed. The piston then passes farther on account of the expansion of the combustion gases, and when the side of the piston exposed to the pressure reaches the edges of the ports (see Fig. 2) the cleaning valve 29 is opened as well as valve 22 in the expansion cylinder. Thereby the combustion gases from cylinder 15 are driven from cylinder 15 first into conduit 21 and then into the expansion cylinder 16. The cleaning is thus effected during the time which the piston 53 holds the ports 19 open or during a part of that time. But it is not absolutely necessary that the filling of the expansion cylinder occur simultaneously with the cleaning of the combustion cylinder. The filling must, however, always take place during the first part of the piston course, counted from the dead-point.

In the piston position according to Fig. 3, or immediately before or after the same, the air and fuel valve 26 of the combustion cylinder is opened, and in consequence of the combustion on the left side of the piston 53, the piston 53 moves to the right while the cleaning valve 29 still remains open. This latter valve is not to be closed before the right side of the piston 53 has entirely passed the ports and even a little beyond it, for instance, to the position shown in Fig. 4.

The perfect regulation of the closing of the cleaning valves 27 and 29 is closely connected with the ignition of the driving-gas mixture on entering the cylinder 15. In the above-described two-cylinder motor a spontaneous ignition is employed, that is, the fresh air pressed into the cylinder is compressed in the known manner to ignition temperature. The degree of compression in question, which ought not to be too high and at all events not too low, depends on the quantity of air inclosed in the cylinder when the cleaning-valve 29 is closed.

I claim—

1. In a gas engine, the combination with a combustion cylinder and piston, and an air

compressor driven directly thereby, of an expansion cylinder and piston and an air compressor driven directly thereby, means to connect the compressors to obtain stage compression, means of communication between the combustion and the expansion cylinders and between the high stage compressor and the combustion cylinder, the high stage compressor compressing the air to ignition temperature previous to admission to the combustion cylinder, and valve controlled connections between the lower stage compressor and combustion cylinder to admit scavenging air to the latter during the exhaust. 75

2. In a gas engine, the combination with a combustion cylinder and piston, and an air compressor driven directly thereby, of an expansion cylinder and piston, and an air compressor driven directly thereby, a fuel reservoir, valves controlling the admission of fuel to the combustion cylinder, means to connect the compressors to obtain stage compression, means of communication between the combustion and the expansion cylinders and between the high stage compressor and the combustion cylinder, the high stage compressor compressing the air to ignition temperature previous to admission to the combustion cylinder, and valve controlled connection between the lower stage compressor and combustion cylinder to admit scavenging air to the latter during the exhaust, said combustion cylinder exhausting into the expansion cylinder. 90

3. In a gas engine, the combination with a combustion cylinder and its piston, said cylinder having exhaust ports therein controlled by the piston and a low stage pressure compressor the piston of which is connected directly to the piston of the combustion cylinder, of an expansion cylinder into which the combustion cylinder discharges, a piston therein; a high pressure compressor the piston of which is directly connected to said piston of the expansion cylinder and discharging into the combustion cylinder, valve-controlled connections between said low stage compressor and the combustion cylinder to admit scavenging air, and valve-controlled connections between the high stage compressor and combustion cylinder to admit air for combustion. 100

In testimony, that I claim the foregoing as my invention, I have signed my name 115 in presence of two subscribing witnesses.

SVEN GUSTAF WIGELIUS.
